UNITED STATES PATENT OFFICE.

WILLIAM A. WEBBER, OF MEDFORD, MASSACHUSETTS.

PNEUMATIC CASH-CARRIER APPARATUS.

SPECIFICATION forming part of Letters Patent No. 378,533, dated February 28, 1888.

Application filed April 13, 1887. Serial No. 234,669. (No model.)

To all whom it may concern:

Be it known that I, WILLIAM A. WEBBER, of Medford, in the county of Middlesex and State of Massachusetts, have invented certain new and useful Improvements in Pneumatic Cash-Carrier Apparatus, of which the following is a full, clear, and exact description.

This invention relates to improvements in pneumatic cash-carrier apparatus, and has for its object the indicating or signaling to the person who has transmitted the carrier or other article through the tube when such carrier or other article arrives at or near the delivery end of the tube or at some desired point or place in the tube, or has been discharged at the delivery end of the tube; and the invention consists, in combination with a pneumatic tube for the transmission of a carrier or other article therethrough, of an independent and supplementary tube or passage having communication with an indicator or signaling or sounding device at or near the transmitting end of the pneumatic tube and with a bellows or collapsible and expansible chamber, which is arranged to be operated by means of an arm or lever extending into the pneumatic tube in position for the carrier, &c., as it is transmitted through the pneumatic tube, to strike and abut against such arm or lever and cause said bellows or collapsible and expanding chamber to close or open, and thus cause air to pass through the independent and supplementary tube or passage and operate the indicator or signaling or sounding device, and thus notify or indicate to the person who transmitted the carrier, &c., that it had been delivered from the pneumatic tube or had passed a desired point or place along the tube, all substantially as is hereinafter fully described, reference being had to the accompanying sheet of drawings, in which—

Figure 1 represents in side view a pneumatic tube for the transmission of cash-carriers or other articles therethrough from one station to another, having attached thereto the present invention. Fig. 2 is a detail vertical section of the bellows or collapsible and expansible chamber, showing its means of communication with the independent tube or passage and its connection with the pneumatic tube for operation by the carrier or other article as it is transmitted through the tube; Fig. 3, a detail ver-

tical section showing the bellows or collapsible and expansible chamber as operated by the carrier in the pneumatic tube. Fig. 4 is a partial side view and partial section of the signaling or indicating apparatus. Fig. 5 is a detail vertical section similar to Fig. 2, to be hereinafter referred to. Fig. 6 is a detail vertical cross-section of the signaling or indicating device at right angles to that of Fig. 4. Fig. 7 is a vertical sectional view of one end of the pneumatic tube and its standard on line 7 7, Fig. 1.

In the drawings, A represents a pneumatic tube for the transmission of a cash-carrier or other article, &c., therethrough, the tube at each end being attached to a separate standard, B, which is secured to any suitable table or desk, as at a, and has a chamber, C, with which said tube communicates, which in turn communicates with any suitable operating bellows or other air-motor.

D is a valve, hinged at b to the standard and adapted to close and open the opening E to the standard-head F, through which opening E the carrier or other article to be transmitted is inserted for such transmission and delivered after having passed through the tube, all substantially as is usual and well known in pneumatic cash-carrier apparatus, and needing no more particular description herein.

G is a tube which extends from one end, H, of the pneumatic tube along with it and toward the other end, K. At the end H this tube G is connected to a small bellows or collapsible and expansible chamber, L, which is attached to and supported by the pneumatic tube A, the tube G having communication therewith, as shown in Figs. 2 and 5. The bellows L is secured by screws d to an arm, M, of a strap, f, which strap encircles the tube, and is held securely thereon by a screw-nut, g, passing through the two ends of the strap by which the bellows L is secured to the pneumatic tube. Attached and pivoted at h within a longitudinal slot, m, of the pneumatic tube, below the bellows L, is an arm or lever, N, in two parts or arms, n r, hinged together, one part, r, extending toward and under the bellows L, and the other part, n, through the slot m into the pneumatic tube, and when the bellows L is open and the parts in their normal position such arm projects into the pneumatic

tube, as shown more particularly in Fig. 2. The hinge-joint of the two arms n r is such that when in the position shown in Fig. 2 the two square ends s s of each arm will abut 5 against each other for the proper operation of the lever, and yet allow the arm n to swing upward on its pivot, independent of the arm r , into the position shown in Fig. 5. The arm r is held to the bottom board, P , by the staple t , 10 to keep it in position ready for proper operation on the bellows, as will be described. The other end, K , of the independent tube G is attached to an arm or block, Q , secured by a bracket, u , to the pneumatic tube A , and 15 communicates with a chamber or passage, R , in said block, which chamber or passage opens into and communicates with a chamber, T , in a vertical cylinder, U , in which is adapted to move freely up and down a piston or valve, V . 20 This piston has a central vertical arm, v , which extends upward through an opening, w , in the top, and engages by an eye, y , with a spring-wire arm, W , having a knob or block, Z , on its outer end and pivoted at a' to an arm, b' , 25 of the cylinder. Attached to an upright arm, d' , of the cylinder is a bell or gong, f' , which is in position for the knob Z of the spring-arm W , as such spring-arm is swung up, to strike against the bell or gong, as shown in dotted 30 lines in Fig. 4, and sound the same, as usual in striking bells or gongs.

The operation of the apparatus is as follows: The carrier or other article to be transmitted through the pneumatic tube is placed in the 35 tube in the head F of the standard B and the valve D closed, and then the bellows or other air-motor operated, which forces the carrier along through the pneumatic tube. When the carrier reaches the part of the pneumatic tube 40 where the bellows L is attached, it strikes against the arm n on the lever N , and as it continues its movement it presses such arm down, swinging it on its pivot h and swinging its arm r up, which in its movements moves up the bottom board, P , of the bellows L and 45 closes the same, as shown in Fig. 3. As the bellows L closes, the air from such is forced along the independent tube to and into the chamber R and the cylinder-chamber T at 50 the transmitting end K of the tube, which raises the piston V , and through it the spring-arm W , which strikes the bell f' and sounds the same, thus notifying the person who transmitted the carrier, &c., that the carrier has arrived at the desired point in the pneumatic 55 tube or has been discharged at the delivery end. After the carrier has passed the arm n the bellows L opens or falls to its normal position, ready for operation when another carrier is transmitted through the tube. When the carrier, &c., is transmitted through the pneumatic tube in the reverse direction, as the carrier reaches the point where the arm n is, it strikes such arm and swings it up on its 60 pivot, in this movement not affecting its arm r , so that the carrier passes freely by the same, the arm lying in the upper part of the slot m , 65

as shown in Fig. 5. Thus the person operating the apparatus to transmit the carrier, &c., through the pneumatic tube is notified by the 70 sounding of the bell or gong that the carrier, &c., has been delivered or arrived at the predetermined point, when he can cease operation of the bellows or other air-motor.

The bellows or collapsible and expansible 75 chamber L can be located at any desired point on the pneumatic tube for operation thereof, at or near the delivery end or at any distance back therefrom, but should be near enough to the delivery end for the carrier, &c., if the operator ceases operation of the motor, to be carried along the balance of the pneumatic tube 80 and delivered therefrom by its momentum.

Although the pneumatic tube shown in the drawings is adapted to transmit a carrier, &c., 85 therethrough from each end, the signaling or indicating device is only arranged for operation by the transmission of a carrier, &c., one way—that is, from the end K to the end H —and for operation the other way the independent tube and its parts must be duplicated; or, if only one independent tube is used, the bellows L and the signaling device should be duplicated and a suitable valve arrangement 90 combined therewith for operation either way—for instance, as shown and described in a joint application, No. 229,192, filed February 28, 1887, of myself and W. S. Pain for Letters Patent of the United States on pneumatic cash-carrier apparatus. 95

Any suitable sounding device can be used, such as a whistle or anything that can be operated from the passage of air through the independent tube or passage; or, in lieu of a sounding device, any suitable indicator for 100 sight observation can be used; also, any suitable bellows or collapsible and expansible chamber can be used, and the lever can be arranged to operate it in any suitable manner, and in lieu of being in two parts it can be in 105 one; but it should be so adjusted that after operation by the carrier, &c., it will return to its normal position for operation again, and also will allow the carrier to pass by it when going in the reverse direction without affecting the bellows; also, in lieu of being independent of the bellows L , it can be attached 110 permanently to the moving board or be an extension of the same. 115

The bellows L and the signaling device can 120 be secured to the pneumatic tube in any suitable manner, and such device can be located in any suitable position away from the tube; also, in lieu of closing the bellows L for the 125 operation of the signaling device, it can be arranged to operate in the reverse—that is, to open or as an exhaust-bellows; but in such case the other parts connected therewith should be reversed accordingly.

Having thus described my invention, what 130 I claim is—

1. The combination, with a pneumatic tube for the transmission of a carrier, &c., there-through, of an independent tube or passage

- having communication with a suitable indicator or signaling or sounding device and with a bellows or collapsible and expansible chamber, said bellows or collapsible and expansible chamber being suitably connected to said pneumatic tube for operation by the carrier, &c., as it travels along the pneumatic tube. 5
2. The combination, with a pneumatic tube for the transmission of a carrier, &c., there-through, and an independent tube or passage having communication with a suitable indicator or signaling or sounding device and with a bellows or collapsible and expansible 10 chamber, of a pivoted lever arranged to act upon said bellows or collapsible and expansible chamber and extending into the pneumatic tube in proper position for the carrier, &c., as it travels along said pneumatic tube, to strike 15 or abut against said lever and operate said bellows, for the purpose specified. 20
3. The combination, with a pneumatic tube for the transmission of a carrier, &c., there-through, and an independent tube or passage having communication with a suitable indicator or signaling or sounding device and with a bellows or collapsible and expansible chamber, of a jointed pivoted lever, one of its arms arranged to act upon said bellows or collapsible and expansible chamber, and its other 25 30 arm extending into the pneumatic tube in proper position for the carrier, &c., as it travels along said pneumatic tube, to strike against said lever and operate said bellows, for the purpose specified. 35

In testimony whereof I have hereunto set my hand in the presence of two subscribing witnesses.

W. A. WEBBER.
